UNITED STATES PATENT OFFICE

ROBERT D. WHITAKER, JR., OF TAHLEQUAH, OKLAHOMA

HOIST

Application filed November 11, 1926. Serial No. 147,768.

This invention relates to certain improvements in hoists; and the nature and objects of the invention will be readily recognized and understood by those skilled in the arts involved in the light of the following explanation and detailed description of the accompanying drawings illustrating what I at present consider to be the preferred embodiments or mechanical expressions of my invention from among various other forms, arrangements, combinations, and constructions of which the invention is capable within the spirit and scope thereof.

It is an object of the invention to provide a power driven hoist of the portable or semi-portable type, particularly adapted for mounting on and use with an automotive or other vehicle for transportation thereby to and from various points of operation and use, such for example as wells, for operation to raise and lower tools, implements, casings, bailers, and the like therefrom and thereinto, or for various other hoisting uses and operations.

Another object of the invention is the provision of a motor driven hoist in which a winding drum is operatively coupled with the motor by clutch mechanism for hoisting and is uncoupled from the motor for gravity lowering, with reversing means operated from the motor for relieving the load on the clutch mechanism to permit of readily uncoupling or disengaging the same to free the drum for gravity lowering therewith.

A further object of the invention is to provide hoisting apparatus of the type in which a winding drum is driven through operative connections from a motor for power hoisting, and clutches are included between the motor and between the drum, and such connections, for uncoupling the motor and drum for gravity lowering, with reverse mechanism for the connections driven from the motor and rendered operative upon disengaging the motor clutch to allow of readily disengaging the drum clutch by relieving the load therefrom, for gravity lowering by and with the disengaged drum.

Another object of the invention is to provide a design, arrangement, and construc-

tion of hoist of the foregoing general type and characteristics, which will be positive and efficient in operation and use, readily operated through the medium of a minimum number of operator controlled members, and capable of general use in various hoisting operations.

With the foregoing and certain other objects and results in view, which will be apparent from the following explanation, the invention consists in certain novel features in construction, and in combinations and arrangements of parts, as will be more fully and particularly referred to and specified hereinafter.

Referring to the accompanying drawings, in which similar reference characters refer to corresponding parts throughout the several figures thereof:

Fig. 1, is a view in elevation of the hoist taken from the motor clutch and drum clutch side thereof.

Fig. 2, is a view in elevation, similar to Fig. 1, taken from the opposite, or reversing mechanism side, thereof.

Fig. 3, is a view in top plan of the hoist.

Fig. 4, is a view in transverse cross-section of the apparatus including the base taken on line 6—6 of Fig. 3.

Fig. 5, is a detailed sectional view of the eccentric bearing mounting for the reversing mechanism.

Fig. 6, is a view in side elevation of a modified form of eccentric bearing of Fig. 5.

The embodiment of the invention presented herein and disclosed in the accompanying drawings, is designed as a portable hoist for mounting on and transporting with a motor truck or the like. However, it is to be understood that the embodiment and use shown herein is purely by way of example and not of limitation, and that a hoist embodying the principles and features of the invention is capable of general use for hoisting or other purposes, and for mounting as portable, semi-portable, or fixed apparatus.

According to the particular embodiment hereof, a hoist of the invention includes a bed, base or supporting frame 10, embody-

ing the side or longitudinal beams 11, transverse end beam 12, and the spaced transverse braces or cross beams 14, with the end cross beam spaced inwardly a distance from the frame end opposite the end beam 12, as will be clear by reference to Fig. 3 in particular of the accompanying drawings. The bed or base 10 is not limited in any manner to the particular construction shown here-with, but is formed as the support or base on and upon which hoisting apparatus of the invention is mounted, and the design and arrangement of the base or bed is determined by the support upon which the bed or base itself is to be mounted.

At the closed end of frame or base 10 adjacent end beam 12, and in this instance between beam 12 and the adjacent cross brace or beam 14, a source of power is mounted, such as the internal combustion motor M mounted and disposed across and transversely of such end of the base. At one end of motor M a friction clutch 15 is operatively coupled therewith in the usual or any other desired manner, and includes the movable clutch disc or plate 15' for movement to and from operative engagement with the motor. The disc 15' is movably mounted on the shaft 16 extended outwardly there-beyond, and a sprocket wheel 17 is fixed on said shaft for rotation therewith. At the opposite end of motor M a friction gear or wheel 18 is mounted for operation by the motor, as by extending the crankshaft and mounting friction wheel or gear 18 thereon.

At the end of frame or base 10, opposite the end on which motor M is mounted, a winding or hoisting drum 20 is mounted between the longitudinal beams 11, on a shaft 21 extending across and between beams 11 and journaled in bearings 22 carried by these beams (see Fig. 3). Drum 20 is fixed to shaft 21 for rotation therewith and a clutch mechanism is provided for driving shaft 21 and drum 20. In this instance a gear 23 of the sprocket type is loosely mounted on shaft 21 adjacent one end of drum 20, and on its outer face carries one plate 24 of a square or box type of clutch. The other plate 25 of the clutch is keyed to shaft 21 for rotation therewith and sliding movement thereon to and from operative engagement with clutch plate 24 and gear 23, so that in operative, clutched engagement of plates 24 and 25, rotation of gear 23 causes rotation of plate 25 and shaft 21 with drum 20 fixed thereon. Any of the suitable or desired operating means for movable clutch plate 25 can be provided, such as the lever handle 26 diagrammatically disclosed in the accompanying drawing and operatively coupled with plate 25 for moving the same to and from engagement, as will be readily understood by those skilled in the art.

Brake mechanism is provided for controlling drum 20, and comprises a brake drum 27 formed at and around the inner end of the hoisting drum, with a brake band 28 mounted in operative relation therewith for operation by the hand lever 29, in the usual manner, and requiring no determined explanation or further disclosure than the dia-grammatical showing thereof in the accom-panying drawings, as such brake and oper-ating mechanism are well known and famili-ar in the art. The mounting of the brake at the inner end of the hoisting drum 20 adjacent the clutch mechanism on shaft 21, permits of a simplified arrangement of op-erating mechanism for the brake and the mounting of the brake lever 29 adjacent the clutch lever 26, so as to localize or central-ize these operating levers at a point within easy reach of an operator.

Adjacent the motor M, a shaft 30 is mounted transversely across frame or base 10, with its outer ends journaled in bear-ings 31 mounted on the side beams 11 of the frame, and a sprocket wheel or gear 32 is fixed on shaft 30, in line with the gear 17 on motor shaft 16, and these sprockets are operatively connected by the chain 33 ex-tending thereover and therebetween for driving shaft 31 from motor M. The shaft 30 is suitably split or divided and a change speed transmission 34 is interposed there-between and coupling the shaft to permit of changing the speed and power at which the driven section or end of shaft 30 is operated. Preferably, although not so lim-ited, the transmission 34 is of the three-speed type and is controlled and operated in the usual manner by any suitable man-u-ally actuated operating means. By the pro-vision of the change speed transmission the hoisting apparatus is enabled to handle a wide range of loads with efficiency, as will appear hereinafter. At the driven end or section of shaft 30, opposite the driving end or section on which sprocket 32 is mounted, a sprocket wheel or gear 35 is fixed for rota-tion by and with shaft 30.

A line shaft 36 is mounted transversely of and across the frame or base 10, parallel with and between shafts 20 and 30, and is journaled in bearings 37 on the side beams 11. A sprocket wheel or gear 38 is fixed on shaft 36 for rotation therewith, in line with the driven sprocket 35 on shaft 30, and is operatively connected with sprocket 35 for operation therefrom by chain 39. At the opposite end of shaft 36, a gear or sprocket 40 is fixed thereon for rotation therewith, in line and operatively connected with sprocket 23 loosely mounted on shaft 21, by the chain 41. Thus, the line shaft 36 connects shaft 21, through chains 41 and 39, with the drive and transmission shaft 30, which is connected with motor M, through

clutch 15 and chain 33. By engaging clutch 15 the motor M drives transmission shaft 30, and in turn shafts 36 and the loose sprocket 23 on drum shaft 21. When it is desired to operate drum 20 for hoisting, the square or box clutch plate 25 is slid by lever 26 into engagement with clutch plate 24 of sprocket 23, and the shaft 21 with drum 20 thereon is rotated for power hoisting from the motor M, through the hereinbefore described operative connections. Upon completion of the hoisting or lifting operation, clutch plate 25 is disengaged to release shaft 21 and drum 20 from driving sprocket 23, and the brake is operated through lever 29 to hold drum 20 in position. The gravity lowering operation can then be carried out by releasing brake 27-28 to permit rotation of and unwinding by drum 20, the drum being controlled during this operation by the brake through lever 29, as will be readily understood.

In order to simplify control and operation, the friction clutch 15 is operable and controlled from the opposite end of the frame or base, adjacent the operating levers 26 and 29, by the rod 42 and connections extending therefrom to movable clutch plate or disc 15' of clutch 15, this clutch operating mechanism being of the usual or other desired type and more or less diagrammatically shown herein and described. Similarly, a motor control is provided (not shown) operable through hand lever 44, at the control end of the apparatus for controlling the motor M during hoisting operations. Preferably, the operating mechanism for shifting or changing the transmission 34, is operable from the control point of the apparatus, that is at the drum end adjacent the above referred to operating levers, although it is not deemed necessary to show such transmission operating mechanism, which can be of any of the familiar types of the art.

In the operation and use of the hoisting apparatus as above described, it is found that difficulty is encountered in disengaging the square or box clutch 24-25 between the shaft 21 and sprocket 23, with the load in hoisted position, due to the transmission of the load onto this clutch tending to force and hold the same in engaged position. The present invention provides as another feature thereof, for the elimination of this difficulty, by means operable simultaneously with release of motor clutch 15, for reversing sprocket 23 and clutch plate 24 to release or relieve the load on clutch 24-25 and permit of its being readily disengaged by hand lever 26. In the particular example of this feature shown herewith, a friction gear or wheel 45 is mounted on a stub shaft 46 in a suitable eccentric or movable bearing 47 supported on frame 10 by a bracket or the

like 48, with gear 45 in alinement with the motor carried and driven friction gear 18. The mounting of friction gear 45 is such that it is normally spaced from and out of engagement with gear 18, but by the eccentric bearing can be swung toward gear 18 to engage the periphery thereof and be driven thereby. On the inner end of shaft 46, a sprocket gear 49 is mounted for rotation by shaft 46 and friction gear 45, and is operatively connected to line shaft 36 through chain 50 and sprocket gear 51 fixed on shaft 36. With motor clutch 15 disengaged and friction gear 45 engaging and driven by motor gear 18, the line shaft 36 and mechanism operatively connected therewith are driven in the reverse direction with the result that clutch plate 24 is rotated in a direction opposite to that which the load imposed on clutch plate 25 tends to rotate the same, and the load is relieved from clutch 24-25 to permit of ready disengagement, for gravity operation of the drum 20, controlled by the drum brake.

Operating mechanism is provided for the movable friction gear 45 to engage and disengage the same with motor driven friction gear 18, and such mechanism is coupled with and actuated by and from the motor friction clutch operating mechanism 43 for simultaneous operation therewith, to engage gears 45-18 upon disengagement of clutch 15, and to disengage such gears on operative engagement of clutch 15. As an example, a rocker lever or rod 52 is mounted for rotation, and is provided at one end with the arm 53 pivotally connected to the clutch operating lever means 42, and at the opposite end with the arm 54 pivotally connected by a rod 55 to the eccentric bearing of friction gear 45, so that upon operation of rod 42 the means 43 connected therewith will rock rod 52, and through arm 54 and rod 55 move gear 45 to and from engagement with gear 18. The arrangement is such, that when means 43 is operated to disengage clutch 15, the gear 45 is moved into operative engagement with gear 18 to cause reversing of shaft 36 and clutch member 24, and when 43 is operated to engage clutch 15, gear 45 is moved from engagement with gear 18. In this manner operation of clutch 15 and of the reversing gears 18-45 is performed simultaneously from and by operation of the manual control lever 42.

The hoist shown and described herein is particularly adapted for mounting on and transportation by a suitable vehicle, such as a motor truck (not shown). The frame or base 10 is mounted and secured on a truck bed or body, in any suitable manner, with the drum end of the hoist extended rearwardly beyond the truck. In the operation of the hoist any desired hoisting cable (not shown) is connected to winding or hoisting

drum 20. With motor M operating, lever 42 is actuated to engage clutch 15, which disengages the reverse mechanism, clutch 24—25 is engaged, and the drum brake 27—28 released, whereupon drum 20 is rotated to wind the cable thereon and raise or hoist the load to which the hoisting cable is attached. When the load is raised to the desired elevation, brake 27—28 is applied to the drum 10 and lever 42 operated to disengage motor clutch 15, which simultaneously engages friction gears 18—45 and reverses rotation of shaft 36 and sprocket and clutch plate 24 to release the load on the clutch 24—25. Upon 15 operation of the reverse mechanism to release the clutch load, lever 26 can be actuated manually to permit of readily disengaging clutch 24—25, after which the load can be lowered by gravity, drum 20 freely rotating 20 to unwind the cable, under control of drum brake 27—28, through brake lever 29. The hoisting and lowering operations above described can then be repeated and continued as required.

Referring to Fig. 6, a modified form of eccentric mounting for the reversing friction gear 45 is shown. In this form of mounting, a bearing 70 is provided in which an eccentric disk 71 is rotatably mounted. 25 This disk 71 is provided with and carries a laterally disposed and inwardly extending pin or stub shaft 72, which is mounted on the disk eccentrically with respect to the axis of rotation of the disk. Upon this stub shaft 72, the reversing friction gear 45, is rotatably mounted. An actuating arm 73 is secured to the disk 71 for rotating the same, for the lower end of this arm 73 is operatively coupled with the rod 55, so that upon 30 operation of rod 55 in the proper direction, the disk 71 is rotated in the bearing 70 and the shaft 72 is swung or moved to carry gear 45 into operative engagement with the motor gear 18 to thereby cause reversing operation 35 of the shaft 36 and the sprocket 23 in a manner and for the purpose hereinbefore described.

While the fundamental and main object and purpose of the reversing mechanism for 40 the hoisting apparatus as above described is to remove the load from the winding drum clutch mechanism, to permit of readily disengaging this clutch, attention is directed to certain further uses and advantages thereof. 45 The reversing mechanism is of utility to lower a load when the weight of such load is not sufficient to unwind the drum by gravity. It is of further utility as an aid or help to the brake when the load is too heavy for 50 the brake mechanism to safely control the lowering of the same by gravity.

Obviously, the various features of the invention are not confined to the portable type of hoist shown or for any particular hoisting 55 operations.

By hoisting apparatus of the invention, efficient operation in power hoisting and gravity lowering is possible, with the elimination of difficulty in disengaging the loaded drum from the power driven operating mechanism when it is desired to permit free rotation of the drum by gravity for lowering a load.

It is also evident that various modifications, variations, changes and substitutions might be resorted to without departing from the spirit and scope of my invention and hence I do not desire or intend to limit myself to the exact and specific disclosures hereof.

What I claim, is:

1. In hoisting apparatus, a motor, a hoisting drum, operative connections from the motor to the drum for driving the latter, clutch mechanism between the motor and said connections, clutch mechanism between the drum and said connections, and means driven by the motor for releasing the load on the drum clutch mechanism to permit of disengaging the same, when the clutch mechanism between the motor and said connections is disengaged.

2. In hoisting apparatus, a motor, a hoisting drum, driving connections from the motor to the drum, clutch mechanism between the motor and said connections, clutch mechanism between the drum and said connections, and means independent of the clutch mechanism between the motor and said connections for reversing said connections to release a load from the drum clutch mechanism upon disengaging said motor clutch.

3. In hoisting apparatus, a motor, a hoisting drum, driving mechanism from the motor to the drum for rotating the latter, clutch mechanism between the drum and driving mechanism, clutch mechanism between the motor and driving mechanism, and normally inoperative means independent of said clutch mechanisms operated by the motor upon disengaging the motor clutch for reversing said driving mechanism to release a load on the drum clutch.

4. In hoisting apparatus, a motor, a hoisting drum, driving mechanism from the motor to the drum for rotating the latter, clutch mechanism between the motor and the drum driving mechanism, operating means for engaging and disengaging said motor clutch, clutch mechanism between the drum and driving mechanism, and normally inoperative means rendered operative and driven from the motor for reversing the driving mechanism upon disengagement of the motor clutch to release the load on the drum clutch mechanism, said reversing means being operatively connected with the motor clutch operating means and rendered opera-

tive by actuation of said means to disengage said motor clutch.

5. In hoisting apparatus, a motor, a shaft disposed substantially parallel with the motor, a chain from the motor to said shaft, clutch mechanism between the motor and said chain, a second shaft, a chain from the first shaft to said second shaft, a hoisting drum, a chain from the second shaft to said drum, a clutch between the drum and the chain driving the same, a friction gear operatively coupled with said second shaft, a friction gear on the motor, said first mentioned friction gear being mounted for movement to engage the motor gear to reverse said shafts with the motor clutch disengaged to relieve the load on said drum clutch.

6. In hoisting apparatus, a motor, a hoisting drum, driving connections from one end of said motor to said drum, a clutch between the motor and said connections, a clutch between the drum and said connections, a friction gear at the opposite end of the motor, a second friction gear operatively connected with said driving connections and movable to engagement with said motor friction gear with the motor disengaged for reversing said driving connections to relieve the load on said drum clutch to permit of disengaging the same.

7. In hoisting apparatus, a motor, a hoisting drum, driving connections from the motor to the drum for rotating the latter, a clutch between the motor and drum driving connections, gearing for reversing rotation of said driving connections driven from the motor, said gearing being inoperative with the motor clutch engaged and operative with the clutch disengaged, and control means for simultaneously operating said clutch and reverse gearing.

Signed at Tahlequah, county of Cherokee, State of Oklahoma, this 12 day of October, 1926.

ROBERT D. WHITAKER, JR.
